G. E. McFADDEN

SPINDLE FOR AN ELECTRIC LIGHTING FIXTURE OR SIMILAR ARTICLE

Filed Aug. 10, 1927

FIG 1

FIG 2

G. E. McFadden
INVENTOR.

UNITED STATES PATENT OFFICE.

GLENN E. McFADDEN, OF KANSAS CITY, MISSOURI.

DESIGN FOR A SPINDLE FOR AN ELECTRIC-LIGHTING FIXTURE OR SIMILAR ARTICLE.

Application filed August 10, 1927. Serial No. 23,057. Term of patent 7 years.

To all whom it may concern:

Be it known that I, GLENN E. McFADDEN, a citizen of the United States, residing at 315 East Winthrop Road, Kansas City, Missouri, have invented a new, original, and ornamental Design for a Spindle for an Electric-Lighting Fixture or Similar Article, of which the following is a specification, reference being had to the accompanying drawing, forming a part hereof.

Figure 1 in the accompanying drawing is

a front view of a spindle for an electric lighting fixture, or similar article, showing my new design.

Figure 2 is a diagrammatic side view thereof.

I claim:

The ornamental design for a spindle for an electric lighting fixture or similar article, substantially as shown.

GLENN E. McFADDEN.
